UNITED STATES PATENT OFFICE.

JACOB F. THEURER, OF MILWAUKEE, WISCONSIN.

FILTER.

SPECIFICATION forming part of Letters Patent No. 624,576, dated May 9, 1899.

Application filed January 24, 1899. Serial No. 703,270. (No model.)

To all whom it may concern:

Be it known that I, JACOB F. THEURER, a citizen of the United States, residing at Milwaukee, in the county of Milwaukee and State 5 of Wisconsin, have invented certain new and useful Improvements in Filters, of which the following is a specification.

My present invention relates to improvements in beer-filters, and more particularly 10 to that type known as "battery-filters."

The invention is illustrated in the accompanying drawings, wherein—

Figure 1 is a vertical sectional view of a portion of a filter, showing two of the elements 15 in place relatively to each other and to the outlet or discharge opening; Fig. 2, a sectional view showing the various parts of one of the elements, the pulp excepted, in a separated position; Fig. 3, a top plan view of one 20 of the elements, the different portions or parts being shown as broken away; Fig. 4, an enlarged sectional view of the central portion of one of the elements, and Fig. 5 a perspective view of a portion of one of the pans or 25 supports.

The object of my invention is to produce a filter which while efficacious in use and compact in structure is nevertheless simple in construction and readily made and assembled.

Referring to the drawings, A denotes the 30 base of the filter-housing, provided with a central discharge-opening B. Upon the base is mounted a shell or casing C, only a portion of which is here shown, the construction 35 of the filter-housing being the same as that shown in my Patent No. 618,964, dated the 7th day of February, 1899. An inlet for the beer in the upper end of the filter is provided and the beer is free to pass down and around 40 each of the filtering elements.

As the present invention has to deal mainly with the construction of the elements themselves, I have omitted the upper portion of the structure.

All of the elements are the same in structure, and while I have shown two in place in Fig. 1 and in practice find it oftentimes desirable to use a greater number, still one can be used alone successfully.

The elements are constructed as follows: I first cast a pan D, provided with a central

opening E and an upstanding rim F, the rim being formed with two offsets or shoulders G and H. (Most clearly shown in Fig. 5.) The bottom of the pan or dish is formed with a 55 series of corrugations radiating from the central opening to the rim, the ridges and valleys formed thereby growing wider as they approach the rim. (See Fig. 5.) Opening E in the center of the pan is defined by a depending 60 flange or boss I, while at a slight distance therefrom, on the under side of the pan or dish, there is formed an annular ring or rib J, which is concentric with the opening. A ring K, of soft rubber, is seated in a groove 65 formed in the pan around the depending flange I; but it will be noted that said ring does not extend across to the rib J, the purpose of which will presently appear. Resting within the pan, upon the ridges thereof 70 and the shoulder G at its outer edge, is a plate L, perforated, as shown, and preferably formed of copper. An opening is formed in the center of the plate and a hub M is securely riveted and soldered thereto. The upper end or face of the hub is flat and is of 75 such width as to pass in between the rim I and ring J when the elements are assembled as shown in Fig. 1. Upon the plate L there is next placed a disk of wire-netting 80 N, preferably sustained by or provided at its outer and inner edges with a rim O. There is next placed within the pan a mass of pulp P, which is compressed to a determinate density. The pulp shown in the drawings is 85 supposed to have been compressed, the pulp in its uncompressed state of course occupying a greater space, and special appliances, forming no part of the present case, are employed for holding the uncompressed mass 90 and pressing it into the pan. Upon the upper face of the pulp layer there is placed a screen Q, formed of relatively heavy woven wire. The central opening in this screen is of a diameter greater than that of the hub, 95 so that when said screen is forced down into the pulp layer there will remain a portion of the pulp still exposed between the hub M and the screen, as shown in Figs. 1, 3, and 4. At the outer edge of the screen there is provided 100 on its under face a rim or ring R, preferably semicircular in cross-section, with the round-

ed face downward. When the screen is forced down into the pulp, this ring serves to further condense the pulp immediately below it and above the shoulder or offset H, causing it to contact more closely with the edge of the pan. In the base A, concentric with the discharge-opening B, there is formed a groove or channel S, in which is placed a gasket of soft rubber, so that when the lower filtering element or pan is put in place the ring J will bear thereon and be pressed into the same when pressure is applied to the upper element, when all are assembled, to cause the parts to come to place and make all the joints tight. It will also be seen that the upper face of the rim, intermediate the opening B and the channel S, bears upon the bottom of the pan intermediate the rim I and ring J and makes, primarily, a metallic contact there-with, though the soft-rubber packing K is compressed and serves to make more certain a tight joint at this point. When the second element is placed upon the first, ring J bears directly upon the pulp in the lower pan around and adjacent to the hub thereof, and when pressure is applied to bring the parts to place said ring will be forced down into the pulp, thereby further condensing the same and causing it to contact closely with the face of the hub. At the same time the upper face or edge of the hub of the lower pan will enter between rim I and ring J, forming a tight joint with the lower face of the upper pan and the soft-rubber packing carried thereby. When the pan is in position upon the lower one, the downwardly-projecting ridges or convolutions of the pan will bear upon the wire screen Q, thereby securely holding the pulp against swelling, while at the same time permitting the free access of beer to the upper face thereof between the ridges.

The beer will pass down through the pulp layers and in so doing will be freed from impurities, the filtered beer passing through the perforated plate L down along the bottom of the pan in the valleys formed therein by the corrugations and discharge into the outlet-opening B. From this it will be seen that the corrugations serve a twofold purpose—first, in forming ridges or projections to hold the pulp of the element below in place, and, secondly, to form ways or channels for the filtered beer as it passes through the pulp. Moreover, the upwardly-extending ridges form a support for the lower perforated plate.

By making the pan or dish in the manner above set forth I find that the pan can be cast so smooth and true as not to need any lathework. By making the hub separate and attaching it to the plate L in the manner above described it can be brought very readily to its proper position with relation to the central opening of the pan. Where the hub and pan are formed integral, it is often necessary to face the hub in a lathe, and in so doing the pan is liable to become sprung or twisted, rendering it unfit for use.

The construction above set forth is very simple, easy to manufacture, and readily put together or assembled.

Having thus described my invention, what I claim is—

1. A pan or dish for filtering elements having its bottom formed with a series of corrugations radiating from its center.

2. A pan or dish for filtering elements having a central opening and a series of corrugations radiating from said opening toward the edge of the pan.

3. A pan or holder for filtering elements having a central opening and a series of corrugations radiating from said central opening toward the edge, said corrugations widening as they approach the edge, substantially as described.

4. A pan for filtering elements provided with a central opening, a flange I extending down from the pan around the opening; and a ring or rib J also extending down from the pan concentric with the flange I, substantially as described.

5. A pan or holder for filtering elements provided with a central discharge-opening; a flange I extending down from the pan about said opening; a ring J also extending down from said pan and concentric with the flange I; and a packing-ring K seated in a recess formed around the base of the flange I, substantially as and for the purpose described.

6. A pan or holder for filtering elements provided with a corrugated bottom and a central discharge-opening; an upstanding rim at the outer edge of said pan; and an offset or shoulder G formed around the rim, substantially as and for the purpose described.

7. A pan or holder for filtering elements having a corrugated bottom and a central discharge-outlet; an upstanding rim formed at its outer edge; and offsets or shoulders G, H, formed upon the rim, substantially as and for the purpose described.

8. A pan for filtering elements having a corrugated bottom and a central discharge-opening; a perforate plate resting upon the corrugations; and an upwardly-extending hub secured to said plate in line with the discharge-opening of the pan.

9. A filtering element comprising in combination a pan provided with a corrugated bottom and a central discharge-outlet; a perforate plate resting upon the corrugation; an upwardly-extending hub secured to said plate in line with the discharge-opening of the pan; a mass of compressed pulp resting on said plate and contacting at its edges against the edge of the pan and the upstanding hub; and means for maintaining said pulp in its proper position in said pan.

10. In a filter, the combination of a suitable base provided with a central discharge-opening; an annular groove or channel formed around said opening and provided with a yielding packing material; a pan resting upon the base, said pan being provided with a down-

- wardly-projecting flange I to enter the discharge-opening; a ring J to act in conjunction with the packing material mounted in the groove or channel; a perforate plate mounted 5 in the pan; an upstanding hub carried by said plate; a mass of filtering material mounted upon said plate within the pan; and a second pan mounted above the lower pan, said second pan having a flange I and a ring J 10 adapted to fit over the upper end of the hub of the lower pan, substantially as and for the purpose described.
11. In a filter, the combination of a suitable base, a discharge-opening formed therein; a 15 groove or channel extending around said opening; a yielding packing material mounted in said channel; and a pan for carrying the filter material resting upon said base, said pan being provided with a downwardly-projecting flange I and an annular ring J, substantially as and for the purpose described.
12. In a filter, the combination of a suitable pan or support carrying a layer of compressed pulp; and a second pan above the first pan, 20 said second pan being provided with a rim or ring on its lower face adapted to bear against the pulp within the lower pan and condense the same, substantially as and for the purpose described.
- 30 13. In a filter, the combination of a suitable pan or support; an upstanding hub for said pan; a layer of compressed pulp carried by the pan and abutting against the side of the hub; and a second pan mounted above the lower pan, said second pan being provided 35 with a depending flange I adapted to enter the upper end of the hub within the lower pan, and also provided with a rib or ring J adapted to act upon the pulp in the lower pan adjacent to the hub, and to further condense 40 the same as the parts are pressed to place, substantially as described.
14. A filtering element comprising in combination a pan provided with a corrugated bottom and a central discharge-opening; a 45 perforate plate L resting upon said corrugations; an upstanding hub M carried by said plate; a disk N formed of wire-netting resting upon said perforate plate; a layer of compressed pulp mounted upon the disk within 50 the pan; a screen Q formed of relatively heavy woven wire mounted upon the upper face of the pulp, said screen having a central opening formed therein of a diameter larger than the external diameter of the hub; 55 a flange I extending down from the pan around the central discharge-opening; and a ring J also extending down from the pan at or near the flange I and concentric therewith, substantially as described. 60

In witness whereof I hereunto set my hand in the presence of two witnesses.

JACOB F. THEURER.
